United States Patent Office

Des. 210,566

Patented Mar. 19, 1968

210,566

KEG CRADLE

Frederic C. Jay, Richmond, Va., assignor to Richmond Cedar Works Manufacturing Corporation, Richmond, Va., a corporation of Virginia

Filed Apr. 17, 1967, Ser. No. 6,729

Term of patent 14 years

(Cl. D94—3)

FIG. 3.

FIG. 1.

FIG. 4.

FIG. 2.

FIG. 5.

FIG. 6.

FIG. 7.

FIG. 8.

FIG. 9.

FIG. 1 is a perspective view of the keg cradle embodying my new design, the keg being indicated in broken lines for illustrative purposes only;

FIG. 2 is a plan view of the cradle;

FIGS. 3 and 4 are elevational views of the two opposite ends of the cradle;

FIG. 5 is a side elevational view thereof;

FIG. 6 is an inverted plan view of the cradle;

FIG. 7 is a section substantially on the line 7—7 of FIG. 2, looking in the direction of the arrows;

FIG. 8 is a section substantially on the line 8—8 of FIG. 2, looking in the direction of the arrows; and

FIG. 9 is a section substantially on the line 9—9 of FIG. 2, looking in the direction of the arrows.

I claim:

The ornamental design for a keg cradle, as shown and described.
